[57] CLAIM

The ornamental design for a combined housing and control panel of an anesthesia machine, as shown and described.

DESCRIPTION

FIG. 1 is a front elevational view of a combined housing and control panel of an anesthesia machine showing our new design;

FIG. 2 is a rear elevational view thereof;

FIG. 3 is a top plan view thereof;

FIG. 4 is a right side elevational view thereof;

FIG. 5 is a left side elevational view thereof;

FIG. 6 is a bottom plan view thereof.

FIG. 7 is a perspective view thereof.

FIG. 1

FIG. 2

FIG. 3

*FIG. 4**FIG. 5**FIG. 6*
